(57) CLAIM

The ornamental design for a brassiere, as shown and described.

DESCRIPTION

FIG. 1 is a front perspective view of a first embodiment of a brassiere according to my new and ornamental design; FIG. 2 is a front elevation view thereof; FIG. 3 is a rear elevation view thereof; FIG. 4 is a right side elevation view thereof; FIG. 5 is a left side elevation view thereof; FIG. 6 is a top plan view thereof; FIG. 7 is a bottom plan view thereof; FIG. 8 is a front perspective view of a second embodiment of a brassiere according to my new and ornamental design; FIG. 9 is a front elevation view thereof; FIG. 10 is a rear elevation view thereof; FIG. 11 is a right side elevation view thereof; FIG. 12 is a left side elevation view thereof; FIG. 13 is a top plan view thereof; FIG. 14 is a bottom plan view thereof; FIG. 15 is a front perspective view of a third embodiment of a brassiere according to my new and ornamental design; FIG. 16 is a front elevation view thereof; FIG. 17 is a rear elevation view thereof; FIG. 18 is a right side elevation view thereof; FIG. 19 is a left side elevation view thereof; FIG. 20 is a top plan view thereof; FIG. 21 is a bottom plan view thereof; FIG. 22 is a front perspective view of a fourth embodiment of a brassiere according to my new and ornamental design; FIG. 23 is a front elevation view thereof; FIG. 24 is a rear elevation view thereof; FIG. 25 is a right side elevation view thereof; FIG. 26 is a left side elevation view thereof; FIG. 27 is a top plan view thereof; and, FIG. 28 is a bottom plan view thereof.

The hatching on the back band of the brassiere indicates that the back band is made of a flat knit fabric. The stippling on the cups of the brassiere indicates that the cups are made of a material other than a flat knit fabric. The dash-dot broken lines indicate the boundaries of the claimed design, which form no part of the claimed design. Portions of the brassiere shown in broken lines beyond the boundaries form no part of the claimed design.

1 Claim, 28 Drawing Sheets
